UNITED STATES PATENT OFFICE.

OTTO WINDECKER, OF KAISERSLAUTERN, GERMANY.

ROLLING-MACHINE.

SPECIFICATION forming part of Letters Patent No. 727,247, dated May 5, 1903.

Application filed August 18, 1902. Serial No. 120,152. (No model.)

To all whom it may concern:

Be it known that I, OTTO WINDECKER, a subject of the German Emperor, residing at Kaiserslautern, Rheinpfalz, Germany, have 5 invented certain new and useful Improvements in Rolling-Machines, of which the following is a specification.

This invention relates to rolling-machines for rolling rods, tubes, and other cylindrical 10 bodies.

According to the invention the billet or block as it passes between the rollers is rotated and moved laterally by the axial movement of the rollers in opposite directions.

15 The invention is illustrated, by way of example, in the accompanying drawings, in which—

Figure 1 is a front elevation, while Fig. 2 is a side elevation corresponding thereto. 20 Fig. 3 is a detailed sectional elevation of one of the rollers and the shaft upon which it is mounted.

In carrying the invention into effect I mount 25 rollers, such as *a b*, so that they may have an axial movement imparted to them in addition to the movement of rotation. The metal block, blank, or billet *g*, previously heated, is placed between the rollers *a b* and passes forward on the rotation of the rollers in an 30 axial direction. Simultaneously with this movement the block, blank, or billet *g* is by the axial movement in opposite directions of the rollers *a b* rotated and caused to move from left to right, so that the block, blank, 35 or billet is rolled circumferentially and reduced.

The rollers *a b* are mounted upon shafts *o* and *v*, respectively, being connected thereto by means of keys *c*. Keyways are provided 40 in the rollers, by means of which the rollers may slide upon the shafts and upon the keys, so as to be compelled by the keys to rotate with the shafts.

The displacement of the rollers during 45 their rotation is effected by means of levers *h*, arranged on each side of the machine, through rods *s*, deriving reciprocating motion from respective toothed wheels *m m*, which gear with pinions *n n*, mounted upon the 50 counter-shaft *w*. The counter-shaft *w* is continuously rotated by means of belting or by gear.

The links *i i* are pivotally connected to the lever *h*, and their opposite extremities are pivotally connected to a bar *p*, which serves 55 to connect together the two rings *r* and *t*, respectively provided on each side of the rollers.

The rollers *a* and *b* are cut down at each side for the reception of the rings *r* and *t* aforesaid, and these rings are provided at diametrically 60 opposite points with pins or projections engaging within holes provided in the respective extremities of the bars *p*. The rings *r* and *t* are thus held against rotation with the rollers *a* and *b*, upon which they are mounted, 65 and serve to effect the axial movement of said links, this movement being communicated to them by the links *i*, which are connected to the bars *p*, as illustrated.

It will be understood that the arrangement 70 is such that on the movement of the lever *h* by means of the connecting-rods *s* the respective links *i* cause the rollers to move axially in opposite directions.

The rotation of the rollers is effected by 75 ordinary gear, as illustrated in the drawings, in which a worm *k* on the counter-shaft *w* causes the rotation of the worm-wheel *d*, which is keyed upon the same shaft as the pinion *e*. The pinion *e* gears with the pinion *y*, arranged 80 on the lower shaft *v*, and also with the intermediate pinion *e'*, which gears with the pinion *x*, arranged on the upper shaft *o*. It will thus be understood that while a slow rotation is given to the respective rollers *a b*, by means 85 of which the block, blank, or billet *g* is slowly fed forward, a relatively quick lateral movement in opposite directions is given to the rollers, by means of which the block, blank, or billet is rolled cylindrically and the formation 90 of flat faces upon the block, blank, or billet is avoided.

Means may be provided for the adjustment of the lateral movement of the respective rollers as required according to the size of the 95 cylindrical body to be formed or according to the dimensions of the blanks, rods, or tubes to be rolled.

What I claim as my invention, and desire to secure by Letters Patent, is—

1. Apparatus for rolling cylindrical bodies in combination, rollers between which the cylindrical body is longitudinally fed, rings at the respective ends of said rollers, bars con-

necting the rings on each roller, and means for giving to the respective bars on each roller an axial movement in opposite directions, substantially as described.

5 2. Apparatus for rolling cylindrical bodies in combination, rollers between which the cylindrical body is longitudinally fed, rings at the respective ends of said rollers, bars connecting the rings on each roller, levers to which said bars are connected respectively

on each side of the pivotal center thereof, and means for reciprocating said levers.

In testimony whereof I have signed my name to this specification in the presence of two subscribing witnesses.

OTTO WINDECKER.
